M. NAKAMIZO.

CARRIAGE TOP EXTENDER.

APPLICATION FILED DEC. 5, 1914.

1,149,163.

Patented Aug. 3, 1915.

UNITED STATES PATENT OFFICE.

MEIJI NAKAMIZO, OF SAN FRANCISCO, CALIFORNIA.

CARRIAGE-TOP EXTENDER.

1,149,163.

Specification of Letters Patent.

Patented Aug. 3, 1915.

Application filed December 5, 1914. Serial No. 875,616.

To all whom it may concern:

Be it known that I, MEIJI NAKAMIZO, a citizen of the United States, residing in the city and county of San Francisco and State 5 of California, have invented new and useful Improvements in Carriage-Top Extenders, of which the following is a specification.

This invention relates to a carriage top extender.

10 When folding or extending carriage tops such as are commonly used on automobiles or the like, it generally requires two persons to accomplish the operation, one on each side of the machine. This is necessary 15 for the following reason: When the top is in the folded position it is first necessary to release the front bows from the rear supporting brackets and lift them forward in unison to the front supporting brackets 20 where they are attached when the top is raised or extended. The bow ends being arranged, one on each side of the machine, cannot very well be handled by one person as they are too far separated to be within 25 his or her reach.

The object of the present invention is to provide a detachable guide bar insertible between the front and rear supporting brackets, one for each side of the machine, 30 which bars are adapted to carry and guide the front bow from one bracket to the other when folding or raising the top, making it possible for one person to accomplish the operation.

35 The invention consists of the parts and the construction and combination of parts as hereinafter more fully described and claimed, having reference to the accompanying drawings, in which—

40 Figure 1 is a plan view of the bow guide as applied with bows folded. Fig. 2 is a side elevation of the same. Fig. 3 is a side elevation of the device with top raised. Fig. 4 is a detail transverse vertical section 45 on line 4—4, Fig. 3. Fig. 5 is a detail view of the rear end of the runway, showing the holding lug contacting with the supporting standard.

More particularly described, A indicates 50 a standard form of foldable automobile top supported by front and rear bows 2 and 3 respectively, which in turn are carried by the front and rear brackets 4 and 5 secured on the body B. In folding up a top of this 55 character it is first accomplished by folding up the front brace rods 6, then pulling out

the cotter pins 7 and releasing the front bow with relation to the supporting brackets 4. The front bow is then carried back and attached to the upwardly turned lugs 8 on 60 the rear bow, which in the meantime has been turned back into the position shown in Fig. 8. To raise or fold a top of this character two persons are required, as one person will have to carry the bow on one 65 side of the machine while the other person carries the bow on the other side, when moving the front bow 2 from one bracket to the other.

The object of the present invention is to 70 provide an attachment which will make it possible for one person to raise or fold the top. This is accomplished as follows: 10 indicates a guide bar, the upper side of which is provided with a channel section 75 11 partly covered by a flange 12. The bar, when in use, is laid across the brackets 4 and 5 and is temporarily secured thereto by a hook-like projection 13, at one end, and a clamp screw 14 at the other end. The channel guide section on top of the bar is open 80 at each end, as at 15 and 16, to permit ingress and egress therethrough, and the channel is slightly curved at each end for purposes hereinafter to be described. 85

The operation will be as follows: When it is desired to raise the top, it is accomplished by first laying a bar across the supporting brackets 4 and 5, one on each side of the machine, and securing same thereto by 90 means of the clamp screws 14. The front bow is then released with relation to the lugs 8 by removing the cotter pins. The tendency of this bow is to spring outward and the bow ends will, therefore, when released, have to be pushed a slight distance forward until the bearing pin 17 of each bow enters the channel of each bar. The person raising the top may now walk to the rear of the machine and lift the top up, causing 95 the rear bow 3 to assume a vertical position while the front bow will be caused to slide forward on the guide bars, as indicated by dotted lines at 18, Fig. 3. The front bow may then be pulled completely 100 over to the front ends of the bars and will then spring out through openings 16 where it may be connected to the front supporting brackets by inserting the bearing pins 17 through the brackets. It is then 105 secured thereto by inserting the cotter pins 7. The front braces 6 may now be opened and

110

- the guy straps (not here shown) attached to secure the top in its raised position. The guide bars may now be removed as the top has been raised and secured in position.
- 5 This is accomplished by releasing the clamp screws 14 and lifting the bars off brackets 4 and 5. The bars may now be laid aside in the machine or placed in the garage for future use as they will not be of any use
- 10 until the top is to be folded. The bars are only temporarily attached when raising or lowering the top and are removed just as soon as this is accomplished.
- 15 The slight curve formed in the channel at each end of the bar is provided for the following reason: After the front bow is released with relation to the rear supporting brackets 5 and the lower ends thereof have been inserted in the channel everything is
- 20 ready and the top may be raised. The raising of the top causes the lower ends of the bow to slide forward in the channels, as indicated by dotted lines in Fig. 3. The curve indicated at 30 permits the tension in
- 25 the bow to be partly released, thereby permitting the bow to slide forward with the least friction possible. The curve indicated at 31 forces the lower ends of the bow inward again, increasing the tension to such
- 30 an extent that when the ends finally enter openings 16 they will immediately spring out into engagement with the front supporting brackets 4 where they are secured by inserting the cotter pins.
- 35 The bars constructed as here shown are simple in construction and are quickly attached or removed. As their attachment is only temporary they do not encumber the machine in any way and, furthermore, make
- 40 it possible for one person to raise or fold the top.

The bars may be attached to and used on any machine where the spread between the supporting brackets is the same, and are

45 equally operable whether the spring in the bows is in an outward or inward direction.

Copies of this patent may be obtained for five cents each, by addressing the "Commissioner of Patents, Washington, D. C."

The materials and finish of the several parts of the device are such as the experience and judgment of the manufacturer may dictate.

I wish it understood that various changes in form, proportions and minor details of construction may be resorted to within the scope of the appended claims and that I do not wish to limit myself to the specific 55 design and construction here shown.

Having thus described my invention, what I claim and desire to secure by Letters Patent is—

1. In a carriage top adjusting device, 60 brackets fixed to the body sides, said brackets having an outwardly extending horizontal member and an upwardly extending perforated member to which the lower ends of the top carrying bows are pivoted, and a 65 channeled guide bar, having an overhanging flange and openings at the ends, said bar being detachably supported upon the horizontal members of the brackets with the openings in line with the pivoted ends of the 70 bows to allow the latter to be transferred to and from the channels.

2. In a carriage top adjusting device, brackets fixed to the body sides, having upturned outer ends, perforated to receive pins 75 at the lower ends of the carriage bows, and intermediate horizontal portions, channel iron guides with means to detachably secure their ends to the horizontal portions, said guides having retaining flanges throughout 80 their length and openings at the ends through which the bow pins may be transferred inwardly into the channels, said guides being curved contiguous to their ends to vary the tension on the moving bow. 85

In testimony whereof I have hereunto set my hand in the presence of two subscribing witnesses.

MEIJI NAKAMIZO.
